EDGAR E. PORTER, OF COLUMBIA, SOUTH CAROLINA.

CENTRIFUGAL GUN.

1,223,069.

Specification of Letters Patent. Patented Apr. 17, 1917.

Application filed August 30, 1916. Serial No. 117,708.

To all whom it may concern:

Be it known that I, EDGAR E. PORTER, a citizen of the United States, residing at Columbia, in the county of Richland and State of South Carolina, have invented certain new and useful Improvements in Centrifugal Guns, of which the following is a specification.

This invention relates to machine guns of the centrifugal type, and the purpose of the invention is to improve the means for feeding and discharging the bullets, and to simplify the aiming of the gun.

Broadly stated, the device involves the use of two coaxial contacting impelling disks which rotate in the same direction at different speeds. One disk has a groove conforming to the longitudinal half section of a bullet. This groove starts as a circular arc near the center of the disk but gradually decreases and then reverses in curvature so as to terminate at the periphery in a radial portion. The other disk has a groove conforming to the transverse half section of a bullet, the groove having a sort of volute contour starting radially outward at the center and terminating in a nearly circular arc portion at the periphery. The two grooves are so designed as to cross each other at approximately right angles in all positions of the disks and receive and confine a bullet of proper shape fed to them at the centers of the disks.

The disks are driven in the same direction at unequal speeds having some simple ratio such as 6:5. A simple ratio is necessary to permit the discharge of the bullets at a constant point. With the mechanism so arranged the bullets are gradually fed outward during a number of turns of the disk and then discharged at a definite point. A driving gear train is devised so as to take its power from a vertical shaft thus permitting the orienting of the gun without affecting the power source. A casing or shell having a barrel tangent to the disks is mounted on trunnions coaxial with the disks and may be shifted by a worm to vary the vertical angle or "elevation" of the discharging bullets.

One embodiment of the invention is illustrated in the accompanying drawing; in which—

Figure 1 is a section on the line 1—1 of Fig. 2;

Fig. 2 is a section on the line 2—2 of Fig. 55 1; and

Fig. 3 is a fragmentary detail of the worm mechanism for elevating the barrel.

In the drawings 6 represents the upper part of a base or pedestal on which the main frame or casing 7 may be rotated on a vertical axis. The main drive shaft 8, which is vertical and may be driven by any suitable motor (not shown), turns in a bearing 9 in the frame 7 and carries a bevel gear 10. The gear 10 meshes with a bevel gear 11 on shaft 12 which in turn drives the shaft 13 through gears 14 and 15. The shafts 12 and 13 are both mounted in frame 7 and the shaft 13 carries fast upon it two unequal spur gears 16 and 17 meshing with a pair of coaxial gears 18 and 19.

The gear 18 which is the smaller is fast upon a stub shaft 20 connected to a disk 21. The gear 19 is fast upon a sleeve 22 which extends from disk 23 and surrounds stub shaft 20. The ratios of gears 16 and 18, and 17 and 19 are so chosen that the ratio of the speeds of disks 21 and 23 is a simple one, the disk 21 moving faster. The ratio 6:5 is a suitable one.

The disk 21 has a projecting tubular sleeve 24 on which it turns. The sleeves 22 and 24 turn in sleeve portions 25 and 26 of a divided casing 27, the casing 27 surrounding the disks 21 and 23 and having a discharge barrel 28 tangent to their peripheries. The sleeves 25 and 26 are mounted in bearings 29 and 30 in frame 7 so that the barrel 28 may be elevated or depressed by swinging the casing 27. Such swinging is effected by rotating a worm 31, which meshes with a wormwheel sector 32 formed on casing 27.

The disk 21 which is the faster moving disk has a groove 33 conforming to the longitudinal half section of the bullet. The groove 33 starts at the hollow sleeve 24 through which the bullets are fed as a circular arc groove, decreases and then reverses in curvature and terminates in a radial portion at the periphery.

The disk 23 which is the slower moving has a groove 34 conforming to the transverse half section of the bullet. The groove 34 starts radially at the center and curves forward, with reference to the direction of rotation, into circular arc form at the periphery. Its position and form are indi-

cated diagrammatically in dotted lines in Fig. 1.

In the drawings the grooves are designed to receive cylindrical bullets with rounded ends.

As will be obvious the crossing of the two grooves affords space to receive a bullet and the differential rotation of the disks which carry the grooves causes the point of crossing of the grooves to move outward. Thus each successive bullet fed into the grooves at the center moves outward from the center and is discharged tangentially at the peripheries of the disk. The rotative speed of the disks is high and yet the differential rotation is relatively slow, thus reducing the shear on the bullets and avoiding much of the difficulty heretofore encountered in feeding the bullets to the point of discharge.

The shell 27 and barrel formed therein are adjusted by means of the worm 31 to determine the elevation or angle of discharge, the barrel serving to determine the trajectory of the bullets exactly as a rifle barrel would do. The range of such adjustment is considerable as the bullets are discharged from the disk some distance to the rear of the point of tangency of the barrel and pursue a curved path within the shell 27 until they reach the barrel 28. The interior of the shell 27 and the barrel may be rifled if desired.

The bullets are fed to the grooves 33, 34 through the axial opening in sleeve 24. The mechanism for doing this may take various forms and is not shown. Any device operable by the rotation of the disks or otherwise to feed the bullets, one at a time, to the grooves might be used, and as such mechanism would confuse the drawings it has been omitted.

In use the shaft 8 is rotated at suitable speed driving the disks through the described mechanism. The gun is aimed by turning frame 7 on base 6 and by tipping shell 27 with its barrel 28 by means of worm 31. Bullets fed in through sleeve 24 and presented to the grooves in the disks are revolved at high speed in a path of increasing radius and then discharged at a high lineal velocity through barrel 28.

The showing in the drawings is largely schematic and various modifications and refinements are obviously possible and are contemplated, the present application being directed to the broader principles involved in the invention.

Having thus described my invention, what I claim is:

1. In a machine gun of the centrifugal type the combination of a pair of juxtaposed coaxial disks provided with complementary bullet receiving grooves on their proximate faces, the groove on one disk being of ap-

proximately volute form and the groove on the other disk being so formed as to cross the groove on the first disk at a progressively changing point in its length as the disks are differentially rotated; and means 70 for imparting differential rotation to the disks.

2. In a machine gun of the centrifugal type the combination of a pair of juxtaposed coaxial disks provided with complementary bullet receiving grooves on their proximate faces, the groove on one disk being of approximately volute form and the groove on the other disk being so formed as to cross the groove on the first disk at approximately a right angle at a progressively changing point in its length as the disks are differentially rotated; and means 75 for imparting differential rotation to the disks.

3. In a machine gun of the centrifugal type the combination of a pair of juxtaposed coaxial disks provided with complementary bullet receiving grooves on their proximate faces, the groove on one disk being of approximately volute form, and the 80 groove of the other disk having a curvature which gradually decreases and then reverses from the center toward the periphery, whereby the two grooves always cross each other substantially at a right angle; and 85 means for rotating said disks at differential speeds.

4. In a machine gun of the centrifugal type the combination of a pair of juxtaposed coaxial disks provided with complementary bullet receiving grooves on their proximate faces, the groove on one disk being of approximately volute form and the groove on the other disk being so formed as to cross the groove on the first disk at a progressively changing point in its length as the disks are differentially rotated; means 100 for rotating said disks at differential speeds having a simple ratio; and an adjustable barrel for receiving and directing the bullets discharged from said grooves at the peripheries of said disks.

5. In a machine gun of the centrifugal type the combination of a pair of juxtaposed coaxial disks provided with complementary bullet receiving grooves on their proximate faces, the groove on one disk being of approximately volute form and the groove on the other disk being so formed as to cross the groove on the first disk at approximately a right angle at a progressively changing point in its length as the disks are differentially rotated; means for rotating said disks at differential speeds having a simple ratio; and an adjustable barrel for 115 receiving and directing the bullets discharged from said grooves at the peripheries of said disks.

6. In a machine gun of the centrifugal type the combination of a pair of juxtaposed 120

- coaxial disks provided with complementary bullet receiving grooves on their proximate faces, the groove on one disk being of approximately volute form, and the groove of the other disk having a curvature which gradually decreases and then reverses from the center toward the periphery, whereby the two grooves always cross each other substantially at a right angle; means for 5 rotating said disks at differential speeds having a simple ratio; and an adjustabl. barrel for receiving and directing the bullets discharged from said grooves at the peripheries of said disks.
- 15 7. In a machine gun of the centrifugal type the combination of a pair of coaxial rotary members having proximate faces provided with complementary bullet receiving grooves, the grooves on the two members being so formed relatively to each other as to 20 cross each other at progressively changing points in their lengths as the members are differentially rotated; and means for imparting differential rotation to said members.
- 25 8. In a machine gun of the centrifugal type the combination of a pair of coaxial rotary members having juxtaposed faces pro-

vided with complementary bullet receiving grooves, said grooves being so formed as to 30 cross each other at approximately a right angle at progressively changing points in the lengths of said grooves as the members are differentially rotated; and means for imparting differential rotation to said members. 35

9. In a machine gun of the centrifugal type the combination of a pair of juxtaposed coaxial disks provided with complementary bullet receiving grooves on their proximate 40 faces, the groove on one disk being of approximately volute form and the groove on the other disk being so formed as to cross the groove on the first disk at a progressively changing point in its length as the disks are 45 differentially rotated; means for rotating said disks at differential speeds having a simple ratio; a casing adjustably mounted concentrically with said disks and provided with a barrel tangent to the peripheries of 50 said disks; and means for adjusting and holding said casing and barrel.

In testimony whereof I have signed my name to this specification.

EDGAR E. PORTER.
